Primary Examiner — Cynthia Ramirez*Assistant Examiner* — Michael A Maharajh(74) *Attorney, Agent, or Firm* — Feeney Law Group;
Alan F. Feeney, Esq.(57) **CLAIM**

I claim the ornamental design for a gua sha tool, as shown and described.

DESCRIPTION

FIG. 1 is a perspective view of a gua sha tool, showing my new design;

FIG. 2 is a top plan view thereof;

FIG. 3 is a bottom plan view thereof;

FIG. 4 is a rear elevational view thereof;

FIG. 5 is a left side elevational view thereof;

FIG. 6 is a front elevational view thereof;

FIG. 7 is a right side elevational view thereof; and,

FIG. 8 is a cross sectional view taken along the line 8-8 in FIG. 2 thereof.

The broken lines in the drawings are for the purpose of illustrating portions of the gua sha tool which form no part of the claimed design.
